BATH MITT

Agnes Ross Baldeschwieler, Asbury Park, N. J.

Application June 16, 1944, Serial No. 540,658

2 Claims. (Cl. 15—227)

This invention relates to bath mitts and more particularly to a device adapted to be worn by a person while bathing, and used the same as one would a wash cloth.

One of the objects of the present invention is to provide a bath mitt of the above general character having relatively few parts which may be inexpensively manufactured and assembled.

A further object is to provide a bath mitt having a plurality of different kinds of fabric which may be used as desired according to the choice of the bather.

A further object of the invention is to provide a bath mitt which may be easily and quickly changed from one hand to the other as desired and to expose any one of the various surfaces to be used against the body.

A further object of the present invention is to provide a mitt which may be worn on either hand with any one of the four surfaces in proper operative relation.

Other objects will be in part obvious from the annexed drawing and in part hereinafter pointed out in connection with the following analysis of this invention.

This invention accordingly consists in the features of construction, combination of parts, and in the unique relation of the various members and in the relative proportioning and disposition thereof, all as more completely outlined herein.

To enable others skilled in the art fully to comprehend the underlying features of this invention and the numerous modifications in structure and relation contemplated thereby, a drawing depicting one of various possible modifications of the invention has been annexed as part of this disclosure, and in such drawing like characters of reference denote corresponding parts throughout all of the views, in which—

Fig. 1 is an elevational view showing the mitt as worn on the left hand of the bather.

Fig. 2 is a plan view of the mitt with certain parts turned back.

Fig. 3 is a detailed sectional view of one end of the mitt in operative position.

Fig. 4 is a detailed sectional view taken on the line 4—4 of Fig. 1.

Referring now to Fig. 1 in which the mitt is shown in operative position on the left hand of the bather, it will of course be appreciated that the mitt may be worn on the right hand and any one of the four different exposed surfaces may be positioned and exposed opposite or adjacent the inner surface of the several fingers to do the

actual rubbing or massaging as desired during the bath.

In this drawing there are two body portions which may be said to be generally elliptical in shape as shown in Fig. 2, and each of these elliptical portions has an outside face preferably made of two different kinds of fabric. For example, the surface 5 between the end and medial line 6 is made of heavy crash or toweling, while the opposite exposed surface indicated at 8 may be made of heavy linen. The opposite side of the adjacent elliptical portion is similarly divided along the medial line 10 into a finer grade of toweling 11, and different grade of crash 12. In fact, the different sections 5, 8, 11 and 12 herein shown may be made of any desired grades of material from a useable linen to a very heavy rough surface as some people prefer one and others a very coarse weave.

20 These two elliptical pieces of fabric are substantially free from each other except for being stitched together along their edges for a distance of approximately one inch at 13 or along the ends of diagonal axes indicated by the dotted lines 14 in Fig. 2. This leaves open spaces at

25 each end of the mitt to permit the hand to be inserted from either end thereby to bring the desired graded cloth adjacent the fingers which really do the washing or massaging action on the skin. The thumb while shown inserted or inside in Fig. 1 may protrude through an opening 15 in

30 the mitt at either side depending upon which hand the mitt is worn which will permit the bather to pick up or hold a cake of soap if desired.

35 When the mitt is in use it is of course desired to keep the fingers concealed within a mitt, as shown for example in Fig. 3. There is therefore provided a cap 16 of relatively fine cloth into which the other or opposite and cooperating elliptical part

40 12 may be inserted. There is of course on the part 12 a corresponding part 17 as shown in Fig. 3 and the fingers may be inserted either beneath this part 17 as shown or between the parts 17 and 12. In either case, the end of the mitt is closed. Of

45 course, the opposite end of the mitt is similarly constructed as indicated by the transverse portions 18 and 20.

The operation and method of using the mitt herein shown and described is clear from the above statement. However, it may be stated that if one has determined the quality of cloth or fabric that he wishes to contact with the skin, let us assume that is the part 8. The adjacent end of the part 12 is slipped beneath the tip 16 of the other part, and the hand inserted through the op-

posite end opening and with the thumb either inside as shown in Fig. 1 or protruding through the opening 15. This opening is sufficiently large to permit the thumb to be extended or retracted as and when desired. At any rate, the device is securely positioned on or about the hand, in either case, and ready for use in a perfectly obvious and well known manner.

The invention is a very simple and practical construction and has relatively few parts which may be easily and quickly assembled with a minimum amount of work and effort. In fact the device is believed to accomplish among others, all the objects and advantages herein set forth.

It may be noted that the mitt may be made in various sizes to suit different members of the family. However, should the mitt be too large and have tendency to slip off the hand in use it may be desirable to turn in the end at the wrist and there is accordingly provided, if desired, a turned back part 19 on the tip 16 as shown in Fig. 3 which part is next to the skin as shown in Fig. 1 and either or both of the ends of the parts 20 and 18 in Fig. 1 may be turned in and then under the part 19 to form a snug wrist engaging cuff.

Without further analysis the foregoing will so fully reveal the gist of this invention that others can, by applying current knowledge, readily adapt it for various applications without omitting certain features that, from the standpoint of the prior art, fairly constitute essential characteristics of the generic or specific aspects of the invention, and therefore such adaptations should and are intended to be comprehended within the meaning and range of equivalency of the following claims.

I claim:

1. A mitt of the class described comprising a pair of superposed elongated flexible plies, said plies being secured together at two spaced locations along their sides and being otherwise unconnected to provide a thumb opening at each side between the said locations thereof and to enable a user's hand to be inserted between the plies through either end of the mitt with either ply disposed across the palm of the hand, finger-receiving pockets, one on each ply on its inner surface adjacent each end and of the same contour as the ends of the plies, the pockets of each ply having entrance openings facing each other, and each pocket being thus positioned so that when the portions of the ply to which the pocket is attached is disposed across the palm of the hand, the pocket is adapted to receive the portion of the ply opposite thereto.

2. A mitt of the class described comprising a pair of superposed elongated flexible plies, said plies being secured together at their sides at two spaced locations, to enable the user's hand to be inserted between the plies through either end of the mitt with either ply disposed across the palm of the hand and the thumb projecting through the openings formed by the spaced securing means at the sides; pockets one on each ply on its inner surface adjacent each end of the ply to which it is attached, the pockets of each ply having entrance openings facing each other, each pocket being thus positioned so that when the portions of the ply to which it is attached, is disposed across the palm of the hand, the pocket is adapted to receive the portion of the ply opposite thereto.

AGNES ROSS BALDESCHWIELER.
